UNITED STATES PATENT OFFICE.

JOHN O'FALLON CLARK, OF CHICAGO HEIGHTS, ILLINOIS, ASSIGNOR TO AMERICAN MANGANESE STEEL COMPANY, OF CHICAGO, ILLINOIS, A CORPORATION OF MAINE.

RAILWAY CROSSING.

Application filed January 9, 1922. Serial No. 527,847.

To all whom it may concern:

Be it known that I, JOHN O'FALLON CLARK, a citizen of the United States, residing at Chicago Heights, in the county of Cook and State of Illinois, have invented 5 certain new and useful Improvements in Railway Crossings, of which the following is a specification.

This invention relates to railway crossings 10 and has for its principal object to provide a crossing composed of a small number of parts connected by joints that will permit the desired flexibility and retain proper alignment of the flange-ways and tread surfaces.

Another object of the invention is to make the mating faces of the joints on straight lines so that they may be readily finished by grinding or similar simple operations.

Another object of the invention is to make 20 a crossing in a minimum number of parts with a maximum interchangeability of parts.

Another object of the invention is to provide a structure in which the securing bolts 25 will be stressed lengthwise only, all tendency to movement transversely to the bolts being resisted by interlocking elements integral with the constituent parts of the crossing.

Another object of the invention is to make 30 the abutting lines or faces of the joints divide the angles between the flange ways.

Further objects of the invention will become apparent as the description is read in 35 connection with the accompanying drawing showing a selected embodiment of the invention, and in which—

Fig. 1 is a plan view of the right angle crossing, one part being displaced to better 40 illustrate the construction;

Figs. 2, 3 and 4 are vertical sectional views taken on the line 2—2, 3—3 and 4—4 of Fig. 1;

Fig. 5 is a plan view of a crossing for 45 acute angles, one part being displaced to better illustrate the construction;

Figs. 6, 7 and 8 are vertical sectional views on the lines 6—6, 7—7 and 8—8 of Fig. 5, and

Fig. 9 is a complementary side elevation 50 of one of the center frogs of the crossing shown in Fig. 5;

Fig. 10 is a plan view of another crossing

for acute angles, two parts being displaced to better illustrate the construction; and 55

Figs. 11, 12, 13 and 14 are vertical sectional views on the lines 11—11, 12—12, 13—13, 14—14 of Fig. 10.

The right angle crossing shown in Fig. 1, is composed of four parts identical in 60 construction. Each part 10 is composed of a body portion 11 of a cross section indicated in Fig. 3, and two wing portions 12 and 13. The body portion 11 is substantially U-shaped in cross-section and the legs 65 are equipped with base flanges 15 to give a wide bearing on the cross ties. The upper surface of the body has a rail head flange 16 and a guard or guide rail flange 17 separated by a wheel flange way 18.

The wings 12 and 13 are also substantially 70 U-shaped in cross section and have similar base flanges to rest upon the cross ties. The upper surface of each wing has a rail head flange 19 and a curved guard or guide flange 75

20 separated by a wheel flange way 21. The flanges 19 and 20 of each wing are adapted to align with corresponding flanges on the body portion of the adjacent part so as to form continuous rail head flanges and 80

guard flanges with continuous wheel flange ways between them. Each wing is also 85 equipped with an extension 22 adapted to be secured to the end of a rail as indicated in Fig. 4. At the junction of each wing with

its body portion, each crossing part 10 is mitered as clearly shown in Fig. 1. The mitered face adjacent to the wing 13 is 90

equipped with lugs 23 adapted to bear on sides of the body and wing portions of the 95

adjacent crossing part. This face is also provided with a groove 24 (Fig. 2) adapted to receive a complementary tongue 25 on the 100

adjacent crossing part. Each crossing part is also provided with a pair of bolt bosses 95

26 at right angles to the mitered joint faces and extending slightly beyond the rear surfaces of the body and wing portions to provide flat faces 27 for the bolt head. Each 105

joint is made fast by two bolts 28 of substantial size passing through these bosses.

From the foregoing it will be clear that the joint faces at the opposite ends of each crossing part 10 are complementary so that any four crossing parts may be assembled to 105 form a crossing. It will also be clear that

the lugs 23 engaging the sides of the body and flange portion will prevent horizontal movement of the crossing parts transversely to the bolts 28 while the tongue 25 fitting in the groove 24 will prevent vertical movement of the parts transversely to the bolts 28. It therefore follows that if the bolts are properly drawn up, the tread faces and wheel flanges will be kept accurately aligned while the necessary amount of flexibility will be present.

In Figs. 5 to 9 I have illustrated a modified form adapted for acute angle crossings. This crossing is also made in four parts, but instead of all four parts being identical they are in two pairs—A and B being the same, and C and D being the same. In this form the end frogs 29 and 30 are substantially the same as the frogs at the four corners of the crossing just described, and the joints being substantially the same in all respects except that the angle of the miter is different and four bolts 31 are used in each joint. The joints at the middle frogs are very similar, but on account of the short faces, it is necessary to secure them in a slightly different manner. Each joint includes a tongue 32 and groove 33 and lugs 34 corresponding to the tongue 25, groove 24 and lugs 23 of the crossing shown in Fig. 1. The crossing parts, however, are provided with ears 35 equipped with aligned bolt holes adapted to receive the securing bolts 36. In this it will be noted that the bolts pass along the sides of the meeting parts instead of through them, underneath the frog. In order to reinforce this joint, I provide a splice plate 37 which underlies a greater portion of the frog and is secured to the ends of the crossing parts by vertical bolts 38 passing through the splice plate and the bosses 39.

In crossings for very acute angles, the joint at the middle frogs of the crossing just described becomes very short, and in order to secure the proper strength, I have provided a six-piece crossing illustrated in Fig. 10. This crossing is composed of three pairs of like parts. The end frogs 40 and 41 are substantially the same as the end frogs of the form shown in Fig. 5 except that the angles, of course, are more acute. The center frogs are identical and are formed by the conjunction of three parts meeting on lines forming a T. A description of one of these frogs will be sufficient to make the construction clear. The ends 42 and 43 have abutting faces 44 and aligned faces 45 and 46 provided with a groove 47 adapted to receive a tongue 48 on the splice piece 49. This splice piece 49 has the sockets 50 adapted to receive lugs 51 on the ends 42 and 43 of the meeting crossing parts. The three parts are secured together by four bolts 52 passed through suitable bosses arranged as indicated in the drawing, and the tongue 48

in the groove 47 prevents vertical movement of the parts transversely to the bolts while the lugs 51 in the sockets 50 prevent horizontal movement transversely to the bolts so that the wheel flange ways and tread surfaces are kept accurately aligned.

From the foregoing it will be clear that I have provided crossing constructions suited to the various conditions imposed by the different angles at which the tracks cross. The right angle crossing makes it necessary to keep in stock only one form of crossing part, four of which can be quickly secured together by eight bolts to form a strong and durable crossing. The modification shown in Fig. 5 requires only two forms of parts, and the modification shown in Fig. 11 requires only three forms of parts. In all forms of construction the mating faces of the joints are formed on straight lines so that the parts may be finished by grinding or other simple mechanical operation. It will be noted that the mating faces at all the joints in the several modifications lie on lines passing approximately through the center of the crossing. This is a very great convenience in assembling the crossing when the work is to be done on the ties.

I am aware that changes in the form and proportion of parts, and in the details of construction of my invention may be made without departing from the spirit or sacrificing any of the advantages thereof, and I reserve the right to make all such changes as fairly within the scope of the following claims.

I claim:

1. In a railway crossing, a plurality of parts having wheel tread surfaces thereon arranged to form a quadrilateral, the joints between the parts being at the corners of the quadrilateral and including mating faces dividing angles between said tread surfaces, bolts securing the parts together and extending transversely to said mating faces, and means to prevent movement of said parts transversely to said bolts.

2. In a railway crossing, a plurality of parts having wheel tread surfaces thereon arranged to form a quadrilateral, the joints between the parts being at the corners of the quadrilateral and including mating faces dividing angles between said tread surfaces, bolts securing the parts together and extending transversely to said mating faces, and means to prevent movement of said parts transversely to said bolts both horizontally and vertically.

3. In a railway crossing, a plurality of parts having wheel tread surfaces thereon arranged to form a quadrilateral, the joints between the parts being at the corners of the quadrilateral and including mating faces dividing angles between said tread surfaces, bolts securing the parts together and extend-

- ing transversely to said mating faces, and tongue and groove elements on said parts at the mating faces to prevent movement thereof transversely to said bolts.
5. In a railway crossing, a plurality of parts having flange ways therein arranged to form a quadrilateral, the joints between the parts being at the corners of the quadrilateral and including mating faces dividing angles between the flange ways, bolts securing the parts together and extending transversely to said mating faces, and interlocking elements on said parts to prevent relative movement thereof transversely to 15 said bolts.
5. In a railway crossing, a plurality of parts having wheel tread surfaces thereon arranged to form a quadrilateral, the joints between the parts being at the corners of the 20 quadrilateral and including mating faces dividing angles between the tread surfaces, bolts passing through said parts transversely to said mating faces, and complementary elements on said parts to maintain the tread 25 surfaces aligned vertically and horizontally.
6. In a railway crossing, a plurality of like parts having wheel tread surfaces thereon arranged to form a quadrilateral, the joints between the parts being at the corners 30 of the quadrilateral and including mating faces dividing angles between the tread surfaces, bolts securing the parts together and extending transversely to said mating faces, and means to prevent movement of said parts 35 transversely to said bolts.
7. In a railway crossing, a plurality of like parts having wheel tread surfaces thereon arranged to form a quadrilateral, the joints between the parts being at the 40 corners of the quadrilateral and including complementary mating faces dividing angles between the tread surfaces and co-acting to maintain the tread surfaces in alignment, and bolts arranged transversely to said mating faces for securing said members together.
8. In a railway crossing, a plurality of parts having wheel tread surfaces thereon arranged to form a quadrilateral, the joints between the parts being at the corners of the 50 quadrilateral and including mating faces substantially straight in one direction, and bolts arranged transversely to said mating faces for securing said parts together.
9. In a railway crossing, a plurality of interchangeable parts joined on lines passing through the center of the crossing, the mating faces of the joints being substantially straight in one direction, means for holding the parts in alignment, and bolts for securing 55 said parts together.
10. In a railway crossing, a plurality of parts each comprising a body portion and wing portions, each body portion having thereon a rail head flange and a guide rail flange separated by a wheel flange way, and each wing portion having a similar rail head flange and guide flange separated by similar wheel flange way adapted to align with the corresponding elements on the body portion of adjacent parts, and means for securing 65 the parts together.
11. In a railway crossing, a plurality of parts having wheel tread surfaces thereon arranged to form a quadrilateral and joined on lines passing through the center of the 70 crossing, mating faces of the joints being substantially straight and extending from the inside to the outside of the quadrilateral, and bolts for securing the parts together.
12. In a railway crossing, a plurality of 80 parts having wheel tread surfaces thereon assembled in angular relation and joined on lines dividing the angle, the mating faces of the joints extending substantially straight through the joint from side to side, interlocking means to prevent sliding movement along said faces and bolts for securing the parts together.
13. In a railway crossing, a plurality of 85 parts each having wheel tread surfaces thereon at an angle to each other, and oblique joint faces adapted to mate when corresponding wheel tread surfaces are aligned, means for securing the faces together and means to prevent sliding movement of said 90 faces.
14. In a railway crossing, a plurality of parts each having wheel tread surfaces arranged at angles corresponding to the angles between the crossing tracks, and straight line 100 faces dividing the angles between the lines of the intersecting rails, interlocking means for holding the wheel tread surfaces on adjacent parts in alignment and means for securing the parts together.
15. In a railway crossing, a plurality of 105 like parts having wheel tread surfaces forming a quadrilateral and straight line faces dividing the angles of the quadrilateral and extending from inside to outside thereof and means for securing the parts together.
16. In a railway crossing, a plurality of 110 parts having wheel tread surfaces thereon, certain of which are interchangeable, said parts having joint faces dividing angles between the lines of the intersecting rails and extending from inside to outside of the crossing, and means for securing the parts together.

JOHN O'FALLON CLARK.
